(57) **CLAIM**

The ornamental design for a water closet, as shown and described.

DESCRIPTION

FIG. 1 is a front view of a water closet embodying my design:

FIG. 2 is a top view thereof;

FIG. 3 is a right side view thereof, the left side being a mirror image of the right side; and,

FIG. 4 is a perspective view thereof.

1 Claim, 2 Drawing Sheets

FIG. 1

FIG. 2

FIG. 3

FIG. 4
